AUTOMATIC SHEET FOLDING AND ENVELOPE FEEDING MACHINE

Ernst W. Kummer, Berlin-Dahlem, Germany

Application September 7, 1955, Serial No. 532,965

12 Claims. (Cl. 53—117)

This invention relates to sheet folding and envelope filling apparatus and particularly to improvements in such apparatus for speeding up operation by providing certain automatically actuated features.

This is an improvement over the sheet folding and envelope filling apparatus disclosed in my copending application Serial No. 477,872 filed December 27, 1954 and in particular it relates to special controls for starting and actuating the mechanism through a cycle.

The major object of the invention is to provide a sheet folding and envelope filling apparatus of novel construction with special power drive and control features.

It is a further object of the invention to provide novel control in sheet folding mechanism.

A further object of the invention is to provide a novel cam and control lever arrangement in a sheet folding and envelope filling apparatus.

A further object of the invention is to provide a novel sheet folding and envelope filling apparatus embodying a power drive and a special automatic drive disconnect after each cycle of operation.

It is a further object of the invention to provide a novel sheet folding and envelope filling apparatus wherein the successive operations are effected through a common drive shaft arrangement having a clutch that disconnects the drive after one operational cycle.

A further object of the invention is to provide a novel sheet folding mechanism control adjacent the envelope mounting station in such apparatus.

Further objects of the invention will appear as the description proceeds in connection with the claims and the annexed drawings wherein:

Figure 1 is generally a perspective photographic view of a sheet folding and envelope filling machine according to a preferred embodiment of the invention;

Figure 2 is a side elevation of the same showing the power drive and clutch controls;

Figure 3 is a top view of the apparatus of Figures 1 and 2;

Figure 4 is a front view of the apparatus of Figures 1-3 showing the trip for the power drive control;

Figure 5 is an enlarged side elevation of the clutch end of the cam shaft;

Figure 6 is a top plan view showing envelope mount structure and adjustment;

Figure 7 is a fragmentary side view that illustrates the cam control of the folding plate; and

Figure 8 is another fragmentary side view that illustrates cam control of the sheet stop fingers and the position adjustment for those fingers.

The apparatus is mounted on a base 11 to which is fixed an electric motor 12 that has its output shaft 13 connected at one end through a suitable gear box to a transverse drive shaft 14 carrying drive pulleys 15 and 16.

A belt 17 connects pulley 15 to a pulley 18 on the shaft 19 of a rubber covered roller 21 constituting the lower member of a paper sheet feed pass having a similar but idly rotatable upper roller 22. Upper roller 22

2

has its ends rotatably mounted in the bifurcated upper ends of the vertical arms of a U-shaped bracket 23 that is suitably pivoted to rock about the axis of shaft 19 and may be locked in adjusted angular position along slot 24 by a clamp nut assembly 25. This adjustment of bracket 23 does not change the separation of the paper feed rollers at the pass but merely the angle and location of the admission throat.

A belt 26 connects pulley 16 to the pulley 27 that is loosely mounted on the end of a cross shaft 28 and adapted to be selectively clutched to shaft 28 at the option of the operator to actuate the apparatus through motor powered drive for a cycle of operation and then to automatically disconnect pulley 27 from shaft 28.

A trip lever 30 is fixed to a transverse rock rod 31 journaled at opposite ends in the support side walls 32 and 33, and lever 30 has a wide handle portion 34 so that it may be more readily actuated. Referring to Figures 2 and 5, an arm 35 is fixed on the end of rock rod 31 and it has an inclined cam face 36 urged against a pin 37 fixed on a latch lever 38 pivoted at 39 on wall 33 and biased clockwise by spring 41. A spring 40 secured at one end to arm 35 normally biases trip lever 30 and arm 35 counterclockwise.

When trip lever 30 is moved clockwise in Figure 2, face 36 cams latch lever 38 to rock counterclockwise about pivot 39. This removes stop face 42 on latch lever 38 from the tip 43 of a lever 44 that is intermediately pivoted about the axis of rod 31 and to which the upper end of spring 41 is connected. Near its upper end lever 44 is pivotally connected at 45 to a guide and support bar 46 slotted at 47 to receive a pin 48 on the end of a crank 49 which is fixed upon a pivoted shaft 51 which also carries the hook lever 110 hereinafter described.

At its upper end lever 44 has a fixed pin 52 upon which bears one end of a lever 53 intermediately pivoted on wall 33 at 54 and biased counterclockwise by spring 55. Thus when lever 44 is unlatched from lever 38 spring 40 pulls it clockwise toward its Figure 5 position and lever 53 follows pin 52 to rock counterclockwise under the influence of spring 55.

Figure 2 shows the parts upon the start of an operation with lever 44 latched by lever 38, and in this condition the end of lever 53 is disposed in the path of a lock pawl 56 freely pivoted at 57 on a disk 58 rigid with shaft 28. In this position pawl 56 has a nose 59 projecting into a notch 61 in the end of a drive pawl 62 that is pivoted on disk 58 at 63 and biased clockwise by spring 64. In this Figure 2 position of the parts shaft 28 is thus locked against rotation although pulley 27 is being continuously rotated from the motor 12.

Therefore when lever 30 is moved clockwise, thereby resulting in counterclockwise rocking of lever 53 about its pivot 54, this removes lever 53 from blocking relation to lock pawl 56 and under the influence of spring 64 the drive pawl 62 is rocked to engage tooth 65 with a unidirectional toothed ratchet member 66 fixed on pulley 27, as shown in Figure 5. Pawl 56 assumes an inoperative intermediate position limited by a fixed pin 66 on disk 58. Now pulley 27 drives shaft 28.

However, when the operator releases trip lever 30 spring 40 pulls it and rod 31 and arm 35 back to the Figure 2 position, and spring 41 pulls levers 38 and 44 back to their latched Figure 2 position. As lever 44 rocks back toward the dotted line position of Figure 5, pin 52 moves along the underside of lever 53 and restores the latter to its Figure 2 position where its end 67 engages and blocks the other nose 63 of lock pawl 56 and swings the latter counterclockwise until nose 59 enters notch 61 and swings drive pawl 62 counterclockwise out of drive engagement with ratchet member 66, and this declutches

the drive and stops rotation of shaft 28. Since, as will appear, in normal operation the operator usually immediately releases lever 30 after moving it to trip position the rotation of shaft 28 is limited to one revolution and the parts are restored to the Figure 2 position awaiting another trip of lever 30.

The particular clutch structure provided between pulley 27 and shaft 28 is not material to the invention which contemplates any suitable clutch there which will accomplish a single revolution of shaft 28 when tripped.

Referring to Figures 1-3 the paper feed station is disposed at 70 and comprises a platform 71 on which may be disposed a stack of paper sheets to be fed one by one into the roller pass 21, 22 by the reciprocating action of intermittent feed roller assembly 72 as determined by a link 73 driven from cam 74 on cam shaft 28 which may be generally the same as disclosed in my copending application Serial No. 468,927 filed November 15, 1954. Sheet side edge guide pads of sponge rubber or the like 75 are connected as by differential threaded couplings to an adjustment rod 76 which has a handle 77, so that rotation of handle 77 in one direction laterally separates pads 75 and rotation of handle 77 in the other direction moves them together. This adjustment regulates the side pressures of the guides 75 on the stack of paper and enables single sheet feed off the top of the stack.

After traversing the roller pass 21, 22 the sheets slide down the inclined table 76 which has parallel vertical side guides 77 and 78 differentially connected to an adjustment rod 79 operated by knob 80 which when turned in opposite directions separates or moves together the side guides 77 and 78.

Table 76 comprises a movable portion consisting of first fold plate 81 that is oppositely pivoted on the side walls at 82 and 83 and a pusher or second fold plate 84 that is slidably connected as by a bar 85 to the underside of plate 81. At pivot 83 a gear 90 is provided meshed with a pivoted segment 86 (Figures 2 and 7) that is connected by pivoted links 87 and 88 and a cam follower roller 89 to a face grooved cam 91 fixed on shaft 28. The lower part of the table is a stationary plate 92 having a plurality of slots 93 up through which project sheet edge contact pins 94.

In operation a sheet passing through the roller pass 21, 22 slides down over inclined stationary table 76, over plates 81 and 84 which are then disposed coplanar with table 76 and over plate 92 to be stopped by their edge contacting stop pins 94.

During the first fold operation plates 81 and 84 swing together as a unit through 180° toward the left in Figures 2 and 7, by the action of cam 91, linkage 87 and 88, gear segment 86 and gear 90. This accomplishes the first fold in the lower third of the sheet and disposes the free end of the paper against the upright surface 190 above resilient throat assembly 100 ready for the second fold operation which is accomplished in timed relation by plate 84 detaching from plate 81 and sliding to the left in Figure 3 with respect to folded-over plate 81. This sliding of plate 84 is sequentially accomplished by having its bar 85 hook in the folded-over 180° position with pivoted lever 110 that is actuated counterclockwise in Figure 2 by cam 111 and associated levers 112 and 113. Fig. 4 as plate 84 slides through the resilient throat assembly it forms the second fold in the sheet and at the same time pushes the accordion folded sheet through the throat 100 into an envelope as will appear. The actuation and operation of pusher 85 and its mounting on plate 81 are essentially the same as disclosed in said Serial No. 477,872. At the conclusion of the first fold operation the pins 94 are pulled down in timed relation out of the path of the sheet, each pin 94 being mounted on a post 95 rigidly upstanding from a rock shaft 96 pivoted to a link 97 controlled by cam 98 on shaft 28. Rock shaft 96 is resiliently biased counterclockwise by spring 99 and the operative longitudinal position of the

pins 94 which are laterally aligned across plate 92 is determined by a slidably adjustable stop 101 that engages an arm 102 rigid with shaft 96.

In Figure 3 are shown fold elements 114 that are swung inwardly across the sheet above plate 92 prior to the first fold operation and then returned to Figure 3 position after the first fold operation and before pusher 84 starts to slide. This is accomplished by cam 115 on shaft 28 which through follower 116 operates lever 117, link 118 and rock rod assemblies 119 that are connected at their lower ends by bar 121. Fig. 4. The purpose of swinging fold elements 114 inwardly is to retain the paper sheet flat on the plate 92 as plates 81 and 84 swing as a unit to overlie plate 92 during the first fold operation. After this first fold is complete elements 114 are swung back to their Figure 3 position so that the pusher 84 can push the partially folded sheet toward the throat assembly 100.

Figure 4 illustrates the cam shaft 28 on which is mounted all of the cams for accomplishing the foregoing in timed relation, and the details not described here and the sequence of operation are the same as disclosed and claimed in my said copending application Serial No. 477,872 filed December 27, 1954 and reference is made to that application for any further detail needed to understand the herein claimed invention.

The resilient flared throat assembly 100 comprises an upwardly curved member 103 that is disposed above plate 92 and presents surface 90. Spring and guide pin assemblies indicated at 104 control separation of member 103 and plate 92 in accord with the thickness of the material passing through it.

At the lower end of plate 92 lower envelope guide plates 105 and 106 are mounted thereon for slidable lateral separation adjustment as by slots 107 and fasteners 108. This provides for different width envelopes to be slipped open-mounted over plates 105, 106 to receive the folded sheet material pushed through the throat by pusher plate 84. The flat side of the envelope is uppermost and slides over the rearwardly extending tongue 109 on throat member 103.

It will be observed that the upper end of the trip lever 30 is disposed just below the envelope filling station at 105, 106 so that when the operator places the open envelope onto plates 105, 106 and tongue 109 he may with a finger of the same hand that holds the envelope there tilt lever 30 toward the apparatus until the latch 38 is tripped. By this action the clutch automatically is engaged to rotate shaft 28 through an operative cycle during which a sheet on the table is accordion folded and pushed through the resilient throat into the envelope being held by the operator's hand at 105, 106, and then stopped, the automatic operation including the feed of another sheet from the stack at 70 through the roller pass and down over the table to rest against pins 94 ready for another fold action.

The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. In a sheet folding and envelope filling machine, means defining a stationary envelope mounting and filling passage, means for folding a sheet and thrusting it into an envelope on said passage defining means, a continuously operable electric motor, normally inactive drive and control means between said motor and said folding means comprising a normally disengaged unidirectional single revolution clutch, and manual means for engaging said

clutch for activating said drive and control means to automatically accomplish a single cycle of operation.

2. In a sheet folding and envelope filling machine, a support means defining a stationary envelope mounting and filling passage mounted in a predetermined fixed location on said support, means for folding a sheet and thrusting it into an envelope on said passage defining means, a continuously operable motor, a rotatable control shaft having thereon elements connected for actuating said sheet folding means, a normally disconnected drive connection between said motor and said shaft comprising a unidirectional clutch, manually operated means for actuating said clutch for establishing said drive connection for driving said shaft through a single cycle of operation of said folding means, and means for then disconnecting said drive connection after a single revolution of said shaft.

3. In the machine defined in claim 2, said manually operated means having a trip member adjacent said passage defining means so that said member may be moved to cause establishment of said drive connection by the hand of the operator placing an envelope on said passage defining means.

4. In a sheet folding and envelope filling machine, means defining a stationary envelope mounting and filling passage, means for folding a sheet and thrusting it into an envelope on said passage defining means, a motor, a continuously operable control shaft having elements thereon connected for actuating said sheet folding means, a normally disengaged clutch between the motor and said shaft, a manual trip member operably connected to said clutch adapted to effect engagement to drive couple the motor to the shaft, and clutch control means driven by said shaft for automatically disengaging said clutch after a predetermined rotation of said shaft.

5. In combination, means defining a stationary envelope mounting and filling passage, a table adjacent said passage, means providing a stack of sheets, means for feeding the uppermost sheet of said stack onto the table, mechanism for folding said sheet on the table and thrusting it into an envelope on said envelope mounting passage, control means operably connected both to said feed means and said mechanism, means for actuating said control means through a single complete cycle wherein a sheet on the table is folded and thrust into an envelope and a fresh sheet is fed onto the table ready for another operational cycle, and means for automatically inactivating said control means after said cycle.

6. In subcombination in a sheet folding and envelope filling machine, a sheet receiving platform having a slot, a sheet edge contacting member projecting through said slot above the platform surface, a pivoted support for said member, and means for actuating said support to withdraw and restore said member through said slot above the platform surface, a pivoted support for said member, and means for actuating said support to withdraw and restore said member through said slot during an operational cycle of said machine.

7. In the subcombination defined in claim 6 an adjustable stop for selecting the operative position of said member along said slot.

8. In a sheet folding and envelope filling machine, a

sheet receiving platform, an envelope mounting funnel at one end of said platform, mechanism for folding a sheet lying on said platform and thrusting it into an envelope held on said funnel by a hand of an operator, and motor driven means for actuating said mechanism having a control handle disposed adjacent said funnel for actuation by said hand of the operator holding the envelope on the funnel.

9. In a sheet folding machine, a table having a plurality of incorporated and associated parts relatively movable to fold an overlying sheet, a control shaft having a plurality of cams connected to sequentially operate said parts, a motor, a continuously operable normally disengaged clutch between the motor and shaft, means for engaging said clutch to drive the shaft from said motor, and means for disengaging said clutch after a single revolution of said shaft.

10. In the machine defined in claim 9, a latch mechanism in the clutch normally holding the shaft idle, said means for engaging the clutch comprising means for releasing said latch, and said means for disengaging the clutch comprising means for releasing said latch, and said means for disengaging the clutch comprising means actuated by the clutch for restoring the latch mechanism to hold said shaft against rotation.

11. In a sheet folding mechanism, a support adapted to underlie a sheet to be folded, means slidable over said support for folding said sheet and thrusting it into an envelope mounting funnel, a pivoted hook member adapted to engage and operate said slidable means, a continuously operable motor, a rotatable shaft having a cam operably connected to said hook member, means including a single revolution clutch mechanism drive for connecting said motor to said shaft, a motion transmitting member connected between said hook member and said clutch mechanism, and a manual trip for said clutch mechanism located adjacent said funnel.

12. In a sheet folding and envelope filling apparatus, a platform for receiving a sheet to be folded, means providing an open envelope mounting funnel at one end of said platform, sheet stops mounted on a pivoted member and projecting above the platform surface adjacent said funnel, means on said platform for folding a sheet lying thereon and thrusting it into said funnel, drive means for periodically actuating said folding means through a predetermined cycle comprising a rotatable shaft, means for automatically withdrawing said sheet stops below the platform surface prior to thrusting said folded sheet into the funnel during each said cycle, means on said shaft and associated resilient means cooperating for moving said pivoted member to withdraw and restore said sheet stops during each cycle, and means for adjusting said sheet stops toward or away from said funnel comprising an adjustable stop determining the pivoted position of said member.
